UNITED STATES PATENT OFFICE.

MAHLON G. BAILEY AND HENRY T. WELCH, OF SAN JOSÉ, ASSIGNORS TO
JAMES G. SPAULDING, OF SAN FRANCISCO, CALIFORNIA.

BOOK-INDICATOR.

SPECIFICATION forming part of Letters Patent No. 480,649, dated August 9, 1892.

Application filed April 6, 1892. Serial No. 428,053. (No model.)

To all whom it may concern:

Be it known that we, MAHLON G. BAILEY and HENRY T. WELCH, citizens of the United States, residing at San José, Santa Clara county, State of California, have invented an Improvement in Book-Indicators; and we hereby declare the following to be a full, clear, and exact description of the same.

Our invention relates to that class of indicators or marks for books in which an indicating-strip lies transversely upon and is movable vertically over the page of the book to indicate the lines thereof.

Our invention consists of a book-mark or line-indicator of this class in which the indicating-strip is made of a thin flexible or pliant sheet of celluloid.

It also consists in a connection or bearing the full width of the indicating strip, whereby said strip is mounted and slides upon its support.

It also consists, in connection with the sliding bearing of the indicating-strip, of a stiffening-sleeve, upon which said bearing is mounted and which is itself mounted and adapted to slide upon the support.

These improvements, together with details of construction and arrangement, will be hereinafter fully described, and specifically pointed out in the claims.

The objects of our invention are, first, to provide in this class of book-indicators an indicating-strip of such a character that by reason of its pliancy and flexibility it will lie perfectly upon the surface of the page of the book; secondly, to hold the indicating-strip perfectly to the support upon which it is mounted by means of such a connection as will enable it to slide up and down upon said support easily without cramping or binding and with precision, and, thirdly, to insure by means of the stiffening-sleeve the extension of the indicating-strip from its support at a right angle under all circumstances.

Referring to the accompanying drawings for a more complete explanation of our invention, Figure 1 is a view of our book-indicator. Fig. 2 is a view showing its application to a book.

A is the indicating-strip. This is a flat thin sheet of celluloid of a flexible and pliant na-

ture, whereby the strip remains always smooth and will lie upon the page B of the book D in perfect contact therewith. It is durable and may be made as ornamental in appearance as desired. Its surface may be ornamented or printed to suit the taste, or it may be so finished as will adapt it to be written upon, so that it may be used for the purpose of making memoranda during its use to indicate the lines, thus rendering it particularly adapted for book-keepers' and accountants' use.

C is the support of the book-indicator. This may consist of any suitable cord or bar, preferably an elastic cord, adapting it to be extended, so that it may fit different sizes of books. This cord is provided at each end with a hook or other fastening c, which engages the leaves of the book at each end, thus holding the cord or support in the fold or bond of the book-back. The indicating-strip has fastened to it at its inner end a tubular bearing a, which, it will be observed, is made of a length equal to the full width of said indicating-strip. This bearing may be mounted directly upon the cord or support C, whereby the indicating-strip A will be adapted to slide up and down on said support, traveling vertically over the surface of the page of the book. This bearing a, being of the full width of the indicating-strip, furnishes a perfectly strong and rigid connection with the cord or support C, which enables the indicating-strip to slide up and down thereon with precision and without any tendency to binding or cramping, as would be the case if said bearing were located at the corner of the strip, or if it were anything less than the full width of said strip. It also causes the indicating-strip to extend from the support or string at a perfect right angle. To insure this latter effect and to render the cord or support C more rigid and less yielding under the movement of the indicating-strip, the bearing a, instead of being mounted directly upon the cord or support C, may be mounted and adapted to slide up and down upon a sleeve E, made longer than the bearing a and fitted upon the elastic string or cord. When the latter is not extended, its diameter is sufficient to snugly fill the sleeve E, whereby the parts remain normally in any position to which they are set; but when the

- cord or support is extended and its diameter thereby decreased the sleeve E can slide readily upon said support or cord. The ends of the sleeve E may be outwardly flanged or provided with burrs e, forming stops, whereby the sliding bearing a is confined upon it and is adapted to pick it up and carry it along up and down over the entire length of the book, so that said bearing a is always upon the sleeve E, which, no matter in what position the indicating-strip may be, will serve the purpose of holding said strip rigidly at right angles and also of stiffening the cord or support C.
- 15 5 This indicator, while useful for any book, is particularly intended for use with the large blank or account books of book-keepers, Government clerks, and others whose duties require the entry of items in large books.
- 20 25 When the strip A is made to write upon, accounts and amounts can be cast up with ease directly below the entries being consulted. The strip A being moved up and down over the surface of the page of the book will accurately indicate any line thereon desired.
- Having thus described our invention, what we claim as new, and desire to secure by Letters Patent, is—
1. A book-indicator consisting of a cord or support to be secured to and lie in the back of a book and an indicating-strip of non-absorbent material having a bearing at its inner end of equal width with the strip and adapted to have a close sliding connection with the cord or support, whereby the strip may be truly aligned with the lines of the book, substantially as herein described.
  2. A book-indicator consisting of a cord or support to be secured to the ends of the book and to lie in the back or bend thereof, an indicating-strip to extend transversely over the surface of the book-page, a sleeve mounted and adapted to slide on the cord or support, and a bearing secured to the inner end of the indicating-strip and mounted and adapted to slide on the sleeve, substantially as herein described.
  3. A book-indicator consisting of a cord or support to be secured to the ends of the book and to lie in the back or bend thereof, a sleeve mounted and adapted to slide upon said cord or support and having end stops, an indicating-strip to extend transversely over the surface of the book-page, and a bearing connected with the inner end of said strip and mounted and sliding upon the sleeve between its stops, whereby by contact therewith said bearing and sleeve move together, substantially as herein described.
  4. A book-indicator consisting of a cord or support to lie in the back or bend of the book and provided with end fastenings for securing it to the ends of the book, a sleeve having end stops and mounted and sliding upon said cord or support, an indicating-strip to extend transversely over the surface of the book-page and made of a flexible or pliant sheet of celluloid, and a bearing secured to the inner end of the indicating-strip and having a length equal to the full width of said strip, said bearing being mounted and adapted to slide on the sleeve between its stops and to carry it with it, substantially as herein described.
  5. In a shifting line-indicator for books, having an elastic guide-cord provided with a slideable sleeve or cover and means for attaching said cord to a book, a pliable sheet of non-absorbent material having a clasp slideable on said sleeve and limited in its movement by the latter, substantially as herein described.

In witness whereof we have hereunto set our hands.

MAHLON G. BAILEY.
HENRY T. WELCH.
